UNITED STATES PATENT OFFICE.

MAE WALLACE McCASTLINE, OF SYRACUSE, NEW YORK.

DESIGN FOR A BADGE OR PIN.

SPECIFICATION forming part of Design No. 24,396, dated June 18, 1895.

Application filed May 2, 1895. Serial No. 547,939. Term of patent 14 years.

To all whom it may concern:

Be it known that I, MAE WALLACE McCASTLINE, a citizen of the United States, residing at Syracuse, in the county of Onondaga and

5 State of New York, have invented and produced a new and original Design for Badges or Pins, of which the following is a specification, reference being had to the accompanying drawing, which shows a front elevation 10 of the badge or pin complete.

The leading feature of my design consists in the grouping or arrangement of the following elements: a ring, a crown of thorns through the ring, and a Latin cross pendent 15 from them, upon a chain, cord or ribbon.

—A— is the ring through which the crown of thorns —a— passes, and —b— is a Latin

cross pendent therefrom upon a chain, cord or ribbon —c—. In each arm of the cross is shown space for any suitable words or in- 20 scription.

A suitable fastening —d— is provided for securing the badge or pin to a garment.

Having described my invention, what I claim, and desire to secure by Letters Patent, 25 is—

The design for a badge or pin, substantially as described.

In witness whereof I have hereunto set my hand on this 29th day of April, 1895.

MAE WALLACE McCASTLINE.

In presence of—

C. W. SMITH,
HOWARD P. DENISON.
